BRIDGE RAILING POST

Charles W. Syak, Girard, and Nick A. Di Margio, Youngstown, Ohio, assignors to Trumbull Development Corporation, a corporation of Ohio

Filed Mar. 18, 1963, Ser. No. 74,025

Term of patent 14 years

(Cl. D28—1)

FIG. 1

FIG. 2

FIGURE 1 is a perspective view of a Bridge Railing Post showing the front and one side thereof, showing our new design;

FIGURE 2 is a perspective view of a Bridge Railing Post showing the back and opposite side thereof modified with a closure strip.

We claim:

The ornamental design for a Bridge Railing Post, as shown and described.
